(57) CLAIM

The ornamental design for make-up packaging, as shown and described.

DESCRIPTION

FIG. 1 is a perspective view of the make-up packaging with a lid, showing the new design;

FIG. 2 is a front view thereof;

FIG. 3 is a back view thereof;

FIG. 4 is a right side view thereof;

FIG. 5 is a left side view thereof;

FIG. 6 is a top view thereof;

FIG. 7 is a bottom view thereof; and,

FIG. 8 is a perspective view thereof, and further showing the lid in an open position, FIGS. 1-7 showing the lid in a closed position.

The design is for make-up packaging. Embodiments of the design include a make-up compact with a lid which opens and closes, a compact with a portion which swings out and in, and a transparent lipstick case.
